INTEREST COMPUTING MACHINE

Miles M. Bartholomew, Meadville, Pa.

Application October 7, 1931, Serial No. 567,409

12 Claims. (Cl. 235—61)

This invention relates to interest computing machines by means of which the amount of interest may be computed on any desired principal and at any desired rate of interest over any desired elapsed time period, and has for its primary object to provide an improved combination and arrangement of principal-counting, elapsed time-measuring, interest rate-changing, and interest-registering devices. A further object of my invention is to provide a mechanism of simple economical construction which may be readily operated by hand to produce the desired computation in a purely mechanical manner. For this purpose, my invention contemplates an elapsed time period gear set comprising a series of coaxially mounted gears having graded numbers of teeth representing respectively different time periods for which any desired rate of interest may be computed; a principal-counting mechanism arranged to be driven in correlation with the elapsed time gear assembly for measuring the desired principal for which the interest is to be computed; an interest rate-changing gear assembly comprising a series of coaxially mounted gears having graded numbers of teeth representing respectively different desired rates of interest at which the interest is to be computed; and an interest-counting mechanism adapted to be operated in correlation with the above-mentioned mechanisms for registering the amount of the desired interest to be computed.

More specific objects of invention will appear in the specification and be pointed out on the drawings in connection with certain features of construction recited in the claims.

The drawings show a preferred embodiment of my invention adapted for the computation of interest connected with various transactions in banking and related spheres of activity. In the drawings,

Figure 1 is a front elevation of a preferred embodiment of my improved interest calculating machine.

45 Figure 2 is a top plan view of the same.

Figure 3 is an enlarged transverse section of the interest-measuring mechanism.

Figure 4 is an enlarged vertical section corresponding to the line 4—4 of Figure 1.

50 Figure 5 is a fragmentary horizontal section on the line 5—5 of Figure 3.

Figure 6 is a schematic top plan view of the gearing trains with the several mechanisms arranged for calculating interest at the rate of 5% over an elapsed time period of 100 days.

Figure 7 is a schematic front elevation of the same.

Figure 8 is a schematic front elevation of the gears similar to that shown in Figure 7 with the several mechanisms arranged for calculating interest at the rate of 6% for an elapsed time period of 30 days.

Referring more particularly to the drawings, a base plate 1 is provided for mounting the several mechanisms in suitable arrangement with respect to each other for permitting the desired adjustments and connections for carrying out any desired interest computation. Journalled at one end in a front supporting plate or bracket 2 and at its rear end in a bracket arm 3 is a rotary shaft 4 to which are keyed a series of elapsed time period measuring gears 5, said gears, in the present embodiment of my invention, being provided with teeth graded in numbers from 10 to 100 for permitting computation of interest over time periods ranging from 10 days to 100 days. Presented forwardly from the front plate 2 is a boss 6 which carries a stud 7 upon which is journalled a gear 8 provided with a rigidly connected crank arm 9. The gear 8 meshes into a pinion 10 of a compound gear which includes said pinion and a larger gear 11, said compound gear being journalled upon a stud 12 which is presented forwardly from the front plate 2. The larger gear 11 of said compound gear meshes into a spur pinion 13 which is keyed to the forward end of the time-measuring spindle 4. For convenience, a finger grip 14 may be mounted on the forward end of the spindle 4 for adjusting the positions of the counters hereinafter to be referred to. A principal-counting and registering device 15 is preferably permanently geared to a particular one of the graded gears 5 of the time period measuring gear cone as shown in Figures 1, 6, 7 and 8. As shown in Figure 6, the 60-tooth gear 5a has been selected as a convenient gear for this purpose, said gear being permanently in mesh with an idler gear 16 which in turn drives two other idler gears 17 and 18, said idler gear 18 being arranged to mesh with a spur pinion 19 keyed to one end of a spindle 20 which is the primary driving spindle of the principal-counting mechanism. Also keyed to the spindle 20 is a relatively broad faced spur gear 21 which as shown in Figure 6 meshes with a lower spur gear 22 which is mounted upon a spindle 23. Keyed to the spindle 23 in the rear of gear 22, is a spur pinion 24 which meshes into a spur gear 25 carried by a spindle 26. A spur pinion 27 which is also keyed to the spindle 26

meshes into a lower spur gear 28 fixed to a spindle 29. A spur pinion 30 which is also keyed to the spindle 29 meshes with an upper spur gear 31 carried by a spindle 32, a spur pinion 33 being keyed to the spindle 32 in the rear of spur gear 31 and meshing into a lower spur gear 34 keyed to a spindle 35. Keyed to the spindle 35 in the rear of gear 34, is a spur pinion 36 which meshes into an upper spur gear 37 carried by a spindle 38. The spindles 20, 26, 32, and 38, above referred to, may constitute the indicator shafts which register the amount of the principal for which the interest computation is being made, said spindles being driven through a chain or gears provided with teeth of suitable numbers for correlating the amounts registered with the other operations of the machine.

Referring now to Figure 2, a pair of parallel guide bars 39 may be rigidly secured to the upper surface of the base-plate 1 to provide inclined guideways for the longitudinal slide 40. Extending longitudinally of the base-plate 1 and parallel to the guide bars 39 is a spline 41 which as shown in Figure 3 operates within a groove 42 in the under surface of the slide 40. The spline 41 as well as the guides 39 are arranged parallel to the slant of the nearer edge of the gear cone 5. The longitudinal adjustment of the slide 40 is designed to permit a time period adjustment of the interest-computing mechanism within any desired limits for which the machine has been designed. As shown in Figures 3 and 5, the slide 40 may be yieldably retained in any adjusted position by means of a reciprocable dog 43 which is pressed by a spring 44 into engagement with a serrated rack-bar 45 formed in the inner wall of the left-hand slotted guide 39, said rack-bar being adapted to slide over the dog 43 as the slide is moved longitudinally of the base-plate 1. As shown in Figures 1 and 4, a fixed stop 46 limits the extreme forward position of the slide 40. As shown best in Figure 4, the slide 46 is provided with parallel transverse guides 47 between which is slidably mounted a transverse slide 48 which is thus adapted to be moved towards and away from the gear cone 5. A dog 49 which is movable in one of the guides 47 under the pressure of a spring 50 is adapted to yieldably interlock with a serrated rack-bar 51 along the adjacent edge of the slide 48 and thus adapted to retain said slide in adjusted position. A fixed stop 52 which projects upwardly from the left-hand lateral edge of slide 48 limits the movement of the slide 48 away from the gear cone 5. Referring now to Figure 3, it will be seen that the slide 48 carries laterally-spaced slotted guides 53 between which a second longitudinal slide 54 is reciprocably mounted on the upper surface of slide 48, the movement of said slide 53 being constrained to an oblique path by means of a spline 55 embedded in the upper surface of slide 48 and projecting into an oblique groove 56 in the under surface of the slide 54. The resulting oblique movement of the slide 54 is in a direction parallel to the slant of the nearer edge of an interest rate-changing gear cone to be presently referred to. The adjustment of this slide 54 is under the yieldable constraint of a dog 57 pressed by a spring 58 into engagement with an inwardly-presented rack-bar 59 in the left-hand slotted guide bar 53. Referring now to Figure 4, the second-mentioned longitudinal slide 54 carries spaced transverse slotted guides 60 between which a second transverse slide 61 is reciprocably mounted on the upper surface of slide 54. Any adjusted position of this second transverse slide 61 may be yieldably maintained by means of a spring-pressed dog 62 operating in the forward transverse slotted guide 60 upon a rack-bar 63 in the adjacent edge of the second transverse slide 61. Mounted upon the upper transverse slide 61 is the interest-counting and registering mechanism which is designated by the general reference character 64. Said interest-counting and registering mechanism is substantially similar in construction to the principal-counting and registering mechanism and is driven by the elapsed time period gear cone through the interest rate-changing mechanism now to be described. As shown in Figures 1 and 2 of the drawings, the transverse slide 40 carries two axially spaced bearing plates 65 and 66. Within said bearing plates is journaled a jack shaft 67 which carries an idler gear 68, said idler gear being arranged to mesh with a spur gear 69 which is keyed to a shaft 70 upon which are coaxially mounted a series of interest rate-changing spur gears which are graded by the numbers of teeth with which they are provided to correspond with various interest rates at which interest is to be computed on a given principal. It will be understood from the description given above of the several slides arranged to the left of the elapsed time period cone gears 5, that the intermediate idler gear 68 may be adjusted longitudinally of the cone gear 5 and moved laterally into mesh with any gear on said gear cone for the purpose of connecting the interest rate-changing gear cone with any gear 5 representing a given elapsed time period. Referring now to Figure 7, the interest-registering mechanism is provided with an intermediate idler gear 72 which may be moved into or out of mesh with any particular gear 71 in the interest rate gear cone. This adjustment is provided for by the movement of the uppermost slide 61 (see Figure 4) which carries the interest-registering mechanism. As shown in Figures 4, 6 and 7, the chain of gears for registering the amount of interest, comprises a series of compound gears 110 driven by a pinion 73 which receives its power from the idler gear 72. The gear train referred to comprises driving pinion 73, lower spur gear 74, lower spur pinion 75, upper spur gear 76, upper spur pinion 77, lower spur gear 78, lower spur pinion 79, upper spur gear 80, upper spur pinion 81, lower spur gear 82, lower spur pinion 83, and upper spur gear 84. The spindles which carry driving pinion 73, upper spur pinion 77, upper spur pinion 81, and upper spur gear 64, constitute the number spindles of the counting mechanism. Said spindles are respectively designated by the reference characters 85, 86, 87 and 88 (see Figure 3). While the counting indicators may, if desired, be mounted directly upon the spindles 135 85, 86, 87 and 88, I prefer to provide counting disks upon which the registering numerals are made of larger size, said counting disks being arranged within the counting mechanism housing. As indicated in Figure 1, I prefer to provide this 140 construction for the principal-counting mechanism as well as the interest-counting mechanism and for this purpose, the front wall or plate of each of said housings is provided with a series of sight openings 89 through which the registering numerals may be read. For the principal-counting mechanism as well as for the interest-counting mechanism, I prefer to employ counting disks of the form shown in Figure 3, this figure showing the particular mechanism employed for 145 150

the interest-counting mechanism. As shown in Figure 3, the driving spur pinion 73 meshes into an idler gear 89 which is interposed between the driving pinion and a spur pinion 90, on an upper counting spindle 91. Said spindle 91 carries a registering disk 92 which is suitably graduated to indicate the number of cents in the amount of interest to be registered. Mounted upon spindle 85 is a disk 93 which carries a radial tooth 94, said radial tooth being adapted to mesh with alternate teeth 95 of a gear carried by a second upper spindle 96 upon which is mounted a second registering disk 97, the gear ratios being suitably designed to rotate the disk 97 once for every ten rotations of the counting disk 92. In a similar manner, a third registering disk 98 is rotated once for every ten rotations of the disk 97; a fourth registering disk 99 is rotated once for every ten rotations of the disk 98; and a fifth registering disk 100 is rotated once for every ten rotations of the disk 99. This particular embodiment of the counting mechanism is therefore adapted to indicate from right to left, cents, dollars, tens of dollars, hundreds of dollars, and thousands of dollars. The indicated amounts, of course, may be indefinitely expanded by the addition of registering disks or by the shifting of the decimal point in a given result. The method of using my improved interest-computing machine will now be understood and may be briefly explained as follows.

Assuming, for example, that interest is to be computed on \$575.00 at 5% for 100 days, the operator imparts a longitudinal movement to the bottom slide 40 to bring the intermediate idler gear 68 (see Figure 2) into transverse alignment with the 100-tooth gear at the extreme front end of the elapsed time cone gear 5. For this purpose, an indicating finger 101 which is mounted on the left forward corner of the slide 40, is movable along a scale 102 on the upper surface of guide bar 39. This adjustment having been accomplished, the lower transverse slide 48 is moved toward the gear cone 5, until the idler gear 68 is enmeshed with the 100-tooth cone gear 5. This step having been accomplished, the upper longitudinally movable slide 54 is next adjusted to bring the idler gear 72 opposite to the particular gear 71 in the interest rate-changing gear cone which represents 5%. This rate of interest is indicated by a scale 103 formed on the upper surface of the lower transverse slide 48 by means of an indicator finger 104 carried by the slide 54. The upper transverse slide 61 which carries the interest-registering mechanism, is then moved toward the interest rate-changing cone gear 71 to bring the interposed idler gear 72 into mesh with the particular gear 71 which represents a rate of 5% interest. With these adjustments made, the crank arm 9 is then rotated until the amount \$575.00 is indicated on the registering disks of the principal item registering mechanism 15. Thereupon, the interest-registering disks on the interest-computing mechanism 64 will indicate the desired amount of interest on \$575.00 for 100 days at 5%. As shown diagrammatically in Figure 8, the relative arrangement of the gears is shown diagrammatically for a similar computation of interest on \$575.00 at 6% for 30 days. For this purpose, the interposed idler gear 68 is arranged to mesh with the 30-tooth gear on the cone gear 5 while the interposed idler gear 72 is arranged to mesh with the gear having 24 teeth on the interest rate-changing gear cone 71, the numbers of teeth in

the several gears 71 being four times the rate of interest at which the computation is made.

I claim:

1. In an interest computing machine, the combination of a main base-plate, an elapsed time gear cone mounted on said base-plate, principal-counting mechanism mounted on said base-plate and permanently geared to said elapsed time gear cone, a main slide reciprocable over an inclined path substantially parallel to the slant of said elapsed time gear cone, a lower transverse slide reciprocable on said main slide towards and away from said elapsed time gear cone, an interest-rate gear cone mounted on said transverse slide and movable thereby into and out of geared connection with any particular one of the gears in the elapsed time gear cone, a longitudinal slide movable obliquely on said lower transverse slide over a path substantially parallel to the slant of the interest-rate gear cone, an upper transverse slide movable towards and away from said interest-rate gear cone, and an interest-counter mounted on the upper transverse slide and movable into and out of geared connection with any particular gear of the interest-rate gear cone. 80 85 90 95 100

2. In an interest computing machine, the combination of an elapsed time gear assembly comprising a series of coaxially-arranged graded gears, principal-counting mechanism geared to said gear assembly, an assembly of coaxially arranged graded interest-rate gears, interest-registering mechanism, means for connecting said interest-rate gears to any gear in said elapsed time gear assembly and means for connecting said interest-registering mechanism to any gear in said interest-rate gear assembly. 105 110

3. In an interest computing machine, the combination of an elapsed time gear assembly comprising a series of coaxially-arranged graded gears rotatable in unison, principal-counting mechanism geared to said gear assembly, an assembly of graded interest-rate gears movable longitudinally and transversely with respect to said elapsed time assembly for connecting said interest-rate assembly with any one of said elapsed time graded gears, and an interest-registering mechanism movable longitudinally with respect to and transversely into and out of geared connection with any particular one of the graded series of gears of said interest-rate gear assembly. 115 120 125

4. In an interest computing machine, the combination of an elapsed time gear assembly comprising a series of coaxially-arranged graded gears rotatable together about a fixed axis, principal-counting mechanism geared to said series of graded gears, a slide movable longitudinally and transversely with respect to said elapsed time gear assembly, an assembly of graded interest-rate gears rotatable together about an axis and carried by said slide for connecting said interest-rate assembly with any one of said elapsed time gears, and an interest-registering mechanism movable longitudinally and transversely with respect to said interest-rate gear assembly and into and out of geared connection with any desired gear of said interest-rate gear assembly. 130 135 140

5. In an interest computing machine, the combination with a principal-counter, of an elapsed time gear cone, means for rotating said elapsed time gear cone and principal-counter, a slide movable over a path extending substantially parallel to the slant of the adjacent side of said gear cone, a second slide movable on the first- 145 150

- 5 mentioned slide over a path extending substantially transversely with respect to the axis of said gear cone, an interest-rate gear cone mounted on the second-mentioned slide, a third slide movable on said second-mentioned slide over a path extending substantially parallel to the axis of said interest-rate gear cone, a fourth slide movable on the third slide in a direction substantially transverse to the axis of said interest-rate gear cone, and an interest-counter mounted on said fourth slide for connecting said interest-counter to any particular gear in said interest-rate gear cone.

6. In an interest computing machine, the combination of a main base-plate, an elapsed time cone gear assembly mounted on said base-plate to rotate about a fixed axis, a principal-counter, means for rotating said elapsed time cone gear and driving said principal-counter in unison therewith, a slide movable on said base-plate over an inclined path substantially parallel to the adjacent edge of said elapsed time cone gear, a second slide movable on the first-mentioned slide towards and away from said elapsed time gear cone, an interest-rate gear cone rotatably mounted on said second slide, a connection gear rotatable with said interest-rate gear cone and movable by said second slide into and out of geared connection with any of the gears in said elapsed time gear cone, a third slide obliquely movable on the second slide along the slant of the nearer side of the interest-rate gear cone, a fourth slide movable on the third slide transversely to the axis of said interest-rate cone gear, and an interest-counter mounted on the last-mentioned slide and movable into and out of position to be geared to any particular gear in the interest-rate gear cone.

7. In an interest computing machine, the combination of a main base-plate, an elapsed time gear assembly mounted on a common axis on said base-plate, said elapsed time gear assembly comprising a shaft rotatable on a fixed axis, a series of graded gears coaxially arranged on said shaft, a chain of gears mounted on said base-plate for driving said shaft, principal-counting mechanism mounted on said base-plate and permanently geared to said shaft, a main slide reciprocable over an inclined path substantially parallel to a plane tangent to the adjacent edges of said series of graded gears, a transverse slide reciprocable on said main slide towards and away from said series of graded gears, graded change gears on said transverse slide movable into and out of geared connection with any of the gears in the elapsed time gear assembly, a longitudinal slide obliquely reciprocable on said transverse slide, a second transverse slide movable towards and away from said time gear assembly, and an interest-counter mounted on the last-mentioned transverse slide and movable into and out of geared connection with said graded change gears on the first-mentioned transverse slide.

8. In an interest computing machine, the combination of elapsed time and principal-counting mechanism, an interest-rate gear cone constructed and arranged to be variably connected to said elapsed time and principal-counting mechanism, variable gear connections interposed between said elapsed time and principal-counting mechanism and said interest-rate gear cone, and an interest-counter movable into and out of geared connection with any particular gear of the interest-rate gear cone.

9. In an interest computing machine, the combination of a main base-plate, an elapsed time gear cone mounted on said base-plate, principal-counting mechanism mounted on said base-plate and geared to said elapsed time gear cone, a slide reciprocable on said base-plate longitudinally of said elapsed time gear cone, an interest-rate gear cone movable on said slide and into and out of geared connection with any particular one of the gears in the elapsed time gear cone, and an interest-counter slidably connected to said slide and movable into and out of geared connection with any particular gear of the interest-rate gear cone.

10. In an interest computing machine, the combination of a main base-plate, elapsed time and principal-counting mechanism mounted on said base-plate and rotatable in unison, an interest-rate gear cone movably mounted on said base-plate, a connection gear rotatable with said interest-rate gear cone, means for connecting said connection gear in variably geared relations to said elapsed time and principal-counting mechanism, and an interest-counter movable longitudinally of said interest gear cone and into and out of position to be geared to any particular gear in the interest-rate gear cone.

11. In an interest computing machine, the combination of a main base-plate, an elapsed time cone gear assembly mounted on said base-plate to rotate about a fixed axis, a principal-counter, means for rotating said elapsed time cone gear and driving said principal-counter in unison therewith, a slide movable on said base-plate adjacent to said elapsed time cone gear, a second slide movable on the first-mentioned slide towards and away from said elapsed time gear cone, an interest-rate gear cone rotatably mounted on said second slide, a connection gear rotatable with said interest-rate gear cone and movable by said second slide into and out of geared connection with any of the gears in said elapsed time gear cone, a third slide movable on the second slide along the interest-rate gear cone, a fourth slide movable on the third slide transversely to the axis of said interest-rate cone gear, and an interest-counter mounted on the last-mentioned slide and movable into and out of position to be geared to any particular gear in the interest-rate gear cone.

12. In an interest computing machine, the combination of an elapsed time gear assembly mounted on a common rotary axis, principal-counting mechanism rotatable with said elapsed time gear assembly, a main slide reciprocable past the adjacent edges of the gears in said gear assembly, a transverse slide reciprocable on said main slide towards and away from said gear assembly, graded change gears on said transverse slide movable into and out of geared connection with any of the gears in the elapsed time gear assembly, a longitudinal slide reciprocable on said transverse slide, a second transverse slide movable towards and away from said time gear assembly, and an interest-counter mounted on the last-mentioned transverse slide and movable into and out of geared connection with any of said graded change gears.

MILES M. BARTHOLOMEW
